CLAIM

The ornamental design for a recessed lighting fixture with a flexible driver assembly, as shown and described.

DESCRIPTION

FIG. 1 illustrates a perspective view of a front side of a recessed lighting fixture with a flexible driver assembly.

FIG. 2 illustrates a top-perspective view of the recessed lighting fixture with an enclosure box shown as being transparent.

FIG. 3 illustrates a bottom-up view of the recessed lighting fixture with the enclosure box shown as being transparent.

FIG. 4 illustrates a top-down view of the recessed lighting fixture with the enclosure box shown as being transparent.

FIG. 5 illustrates a first side view of the recessed lighting fixture with the enclosure box shown as being transparent; and,

FIG. 6 illustrates a second side view of the recessed lighting fixture with the enclosure box shown as being transparent. Broken lines shown in the drawings represent portions of the recessed lighting fixture with a flexible driver assembly that form no part of the claimed design.
